UNITED STATES PATENT OFFICE.

FRANK W. INGOLS, OF CHICAGO, ILLINOIS.

HEADLIGHT.

Application filed March 24, 1920. Serial No. 368,562.

To all whom it may concern:

Be it known that I, FRANK W. INGOLS, a citizen of the United States, and a resident of the city of Chicago, in the county of Cook and State of Illinois, have invented certain new and useful Improvements in Headlights; and I do hereby declare that the following is a full, clear, and exact description of the same, reference being had to the accompanying drawings, and to the numerals of reference marked thereon, which form a part of this specification.

This invention relates to a safety headlight lens and particularly to a headlight lens which is adapted to convert an ordinary headlight into a safety headlight of the type shown and described in my co-pending application for patent, Serial No. 368,561, filed of even date herewith. Headlights of the type under consideration are primarily designed for use with vehicles, and while it is desirable that the glare therefrom above a certain definite plane be eliminated, it is also desirable that this effect be attained with a minimum loss of light flux and that the rays which are not used in the illumination of the surface over which the vehicle is traveling be utilized to provide a comparatively dim source of illumination at the upper part of the headlight. It is of course also desirable that means be provided whereby these superior effects may be attained by a simple adaptation of headlights of usual and well-known construction.

It is an object therefore of the present invention to provide a headlight attachment whereby a main shaft or beam of light is directed below a horizontal plane passing through the axis of the headlight.

It is another object of this invention to provide a headlight attachment having adjustable means for directing and limiting the major portion of the light emanating therefrom.

It is a further object of this invention to provide an attachment adapted to be applied to a headlight to afford simultaneously bright and subdued illumination from a single source.

It is an important object of this invention to provide a headlight attachment having means associated therewith for defining the shaft or beam of light emanating from the headlight and for directing the same.

Other and further important objects of this invention will be apparent from the

disclosures in the specification and the accompanying drawings.

The invention (in a preferred form) is shown on the drawings and hereinafter more fully described.

On the drawings:

Figure 1 is a central vertical section taken through a headlight equipped with the improved attachment of this invention. 65

Figure 2 is a slightly reduced section on the line 2—2 of Figure 1.

Figure 3 is a central vertical section through a headlight equipped with a modified form of attachment. 70

Figure 4 is an enlarged sectional detail of the adjusting means for the headlight attachment.

As shown on the drawings:

The device of this invention is adapted to 75 be secured to an ordinary headlight casing 1 which is provided with a source of illumination at 2 ordinarily coincident with the axis thereof. A lens 3 having a frosted or translucent upper half 4 is secured in the front of said casing 1 in the usual manner by a rim 5, and supported in the casing 1 and surrounding the source of light 2 is a reflector 6, the upper portion of which extends outwardly and is curved downwardly until the same contacts the lens 3 along a line coinciding with the bottom of the translucent portion 4 thereof. 85

The lower portion of the reflector 6 extends around the source of light 2, ordinarily an incandescent electric light bulb, and converges towards the axis of the casing to a point 7 and from said point 7 said reflector is provided with a plurality of steps or ridges 8 which extend downwardly in 90 the casing to the lower edge of the lens 3. Said steps or ridges are each at the proper angle so that light striking the same is reflected upwardly to the top portion of the reflector 6 but is not reflected outwardly 95 through the lens 3. 100

In order that a certain amount of upwardly reflected light in the reflector 6 may afford a diffused or dim source of illumination through the translucent portion 4 of the lens 105 3, an opening 9 is ordinarily provided in the upper portion of the reflector 6 and if desired said opening may be covered by a lens 10 as shown in Figures 1 and 2.

It is to be noted that in this construction 110 there are two separated lines which define the upper limits of the bright beam of light

emanating from the headlight, said lines extending transversely from the casing and being coincident with the point 7 and with the points of contact of the upper portion of 5 the reflector 6 with the lens 3 or the lower edge of the frosted portion 4.

Said bright beam of light is directed downwardly onto the surface over which the vehicle on which the headlight is mounted 10 is traveling and serves to efficiently illuminate said surface without giving an objectionable upward glare.

In the device shown in Figures 3 and 4, the casing 11 of the headlight is provided 15 with a source of illumination 12 which is surrounded by a reflector 13 adapted to direct the main or bright beam of light outwardly from the headlight through a lens 14. Said lens 14 is supported in or is integral 20 with a casing 15 which is adjustably mounted in the rim 16 of the headlight on an extension rim 16^a, and which is preferably constructed of translucent material. The upper portion of said casing 15 curves downwardly and outwardly to a point 17 slightly below the axis of the casing 11 and at 25 said point 17 said casing 15 is provided with walls 18 extending inwardly forming a funnel opening through which the main beam 30 of light is projected from the lens 14.

In this style of the invention, the bright part of the beam of light is limited by the edge 17 of the forward portion of the casing 15 and by the rear edge of this casing 35 which is found at the bottom of the lens 14. These two edges comprise the defining or limiting points for the bright beam of light.

In order that the direction of this bright beam may be varied, means are provided 40 whereby the casing 15 may be rocked inwardly and outwardly in the rim 16. For this purpose a flanged rim 19 is secured to said rim 16^a outside the casing 15 and has extending through the upper portion thereof 45 of a pin 20 on which a cylinder 21 having an eccentrically mounted pin 22 therein is non-rotatably mounted. The pin 22 in the cylinder 21 extends through a slot 23 in an inwardly extending bracket 24 and since 50 said bracket is secured to the upper portion of the casing 15, rotation of the pin 20 acts to move the pin 22 in the slot 23 and rocks the casing 15 inwardly or outwardly in the rim 19 and changes the position of the

means limiting the bright beam. This arrangement of course enables the operator of the headlight to change the angle of downward direction of the main beam of light. 55

While practical embodiments of my invention have been shown and described herein, it is not purposed to limit the same to the specific construction set forth, the novel idea of the invention being to provide a headlight converter wherein separated 60 means extending transversely of the headlight casing act to define and direct the main or bright beam of light downwardly 65 to eliminate objectionable glare without sacrificing illumination efficiency. 70

It is of course apparent that in the constructions shown in Figures 3 and 4 certain of the light from the reflector 13 will act to afford a source of illumination for the upper part of the translucent casing 15 and 75 thus provide a dim or signal light.

I claim as my invention:

1. In a headlight comprising a casing, a source of light, a reflector and a transparent closure, means between the reflector and closure comprising an extension on one of them for establishing a boundary to the bright portion of the beam of light and to cause the bright beam of light to issue below the axis of the headlight, said means including a non-transparent portion extending from said beam upwardly and another non-transparent portion extending from said beam downwardly, the edges of said portions being approximately in the same horizontal plane. 85

2. In a headlight comprising a casing, a source of light, a reflector and a transparent closure, a funnel-shaped translucent casing projecting rearwardly and integral with the lower half of the closure, an inclined condensing lens at the inner opening of the funnel-shaped casing and in front of the reflector to cause the deflection of the bright beam downwardly below the horizontal axis of the headlight, said funnel-shaped casing serving as a boundary to the bright portion of the beam. 95 100
